Samuel Kislovitz, Inventor
By his Attorney Chas. C. Gill

UNITED STATES PATENT OFFICE.

SAMUEL KISLOVITZ, OF HOBOKEN, NEW JERSEY, ASSIGNOR TO CHARLES A. BLADES, OF ARLINGTON, NEW JERSEY.

EASEL.

1,056,183.

Specification of Letters Patent. Patented Mar. 18, 1913.

Application filed December 2, 1912. Serial No. 734,449.

To all whom it may concern:

Be it known that I, SAMUEL KISLOVITZ, a subject of the Czar of Russia, and a resident of Hoboken, in the county of Hudson and State of New Jersey, have invented certain new and useful Improvements in Easels, of which the following is a specification.

The invention pertains to the character of easels attached to the back of and adapted to support in an inclined standing position display cards, photographs and the like, and its object is to provide an easel capable of ready attachment to the back of the card and of having its foldable brace member or members conveniently and securely locked in operative position.

My invention relates more particularly to the novel interlocking members presented herein for securing the brace part or parts of the easel in operative position, said members being formed from the material of the easel and capable of ready manipulation. The easel will preferably be formed in one integral piece from cardboard, strawboard or the like and when not in use may lie flat so as to occupy the minimum amount of space. The easel of my invention may be formed with one brace-member or two brace-members, as may be desired or the use of the device require.

The invention consists in the novel features hereinafter described and claimed and is illustrated in the accompanying drawings, in which:

Figure 1 is a back view of a display card having the easel of my invention secured thereto, the easel being shown in its flat non-supporting position and as having two brace-members; Fig. 2 is a like view of the same, the brace-members being shown as having been turned outwardly at an angle to the card and locked in supporting position; Fig. 3 is a vertical transverse section through the same on the dotted line 3—3 of Fig. 2; Fig. 4 is a horizontal section through the same on the dotted line 4—4 of Fig. 2; Fig. 5 is a detached perspective view of my easel when constructed with only one brace-member, said member being shown as having been turned to its operative position, the securing devices being illustrated as partly interlocked, and the upper locking tongue being shown as ready to be turned downwardly to engage the upper end of the locking section carried by the brace-member and

complete the locking of said member, and Fig. 6 is a rear elevation, on a smaller scale, of the single brace easel represented in Fig. 5, the easel being shown in its flat inoperative position.

In the drawings, 10 designates a display card, photograph mount or the like of usual character, to the back of which my easel is secured by pasting or otherwise.

The easel, referring to Figs. 1, 2, 3 and 4, comprises, in one integral piece, a back-member 11 to be pasted or otherwise attached to the card 10 and two brace-members 12, which correspond with each other and at their inner edges join the back-member 11 along vertical scored or weakened lines, represented at 13, so as to lie flat, as shown in Fig. 1, or be turned or bent outwardly at an angle to the card 10, as shown in Figs. 2, 3 and 4.

In the back 11 I form upper and lower corresponding locking tongues 14, 15 by slitting the material of the easel transversely, as at 16, and approximately vertically, as at 17, said slits defining the outer ends and sides of said tongues. The upper tongue 14 is connected with the back 11 along a transverse score or weakened line 18, and the lower tongue 15 is connected with the back 11 along a transverse score or weakened line 19. The tongue 14 may be turned outwardly and upwardly on the hinge-line 18, and the tongue 15 may be turned outwardly and downwardly on the hinge-line 19, as shown, and said tongues 14, 15 are each formed with two transverse slots, those in the tongue 14 being numbered 20 and those in the tongue 15 being designated 21.

The brace-members 12 are formed, from the material thereof, with corresponding vertical locking sections 22 which, in the blank or flat condition of the easel, extend along the opposite side edges of the tongues 14, 15 and have their free vertical edges defined and formed by the slits 17. The upper and lower ends of the sections 22 are formed by slits 23 which are about on horizontal planes with the hinge-lines 18, 19 for the tongues 14, 15, and said sections at their non-free edges are joined to the brace-members 12 along vertical score or weakened hinge-lines 24, so that they may be turned outwardly at an angle to the members 12 when the easel is to be put into use. The upper and lower ends of the sections 22 are

formed with projecting tongues 25 of a size adapted to receive upon them the slots 20, 21 of the tongues 14, 15 when said sections and tongues 14, 15 are placed in interlocking relation with one another.

When the easel is to be placed in use the tongue 14 will be turned upwardly, the tongue 15 downwardly, the sections 22 outwardly at an angle to the brace-members 12 and said members 12 outwardly toward each other at an angle to the back 11, and thereupon the upper tongue 14 will be closed downwardly upon the upper ends of the sections 22 and the lower tongue 15 upwardly against the lower ends of the sections 22, the whole being locked together by the fact that the slots 20 pass upon and engage the upper tongues 25 of the sections 22 and the slots 21 pass upon and engage the lower tongues 25 of said sections, as shown in Figs. 2, 3 and 4.

The locking means presented by me result, in use, in both brace-members 12 being securely held in their operative position.

In many instances an easel having only one brace-member will be sufficient, and therefore in Figs. 5 and 6 I illustrate my invention as embodied in a single-brace easel, whose construction and operation will be readily understood without special detailed explanation in view of its substantial correspondence with the structure shown in Figs. 1 to 4 inclusive. In Figs. 5 and 6 the back of the easel is numbered 26 and the brace-member 27; the back 26 is formed with upper and lower hinged tongues 28, 29 corresponding with one vertical half of the aforesaid tongues 14, 15, and the member 27 is formed with a vertical hinged locking section 30 substantially corresponding with one of the aforesaid sections 22 and having on its ends tongues 31 to receive the slots 32 in the said tongues 28, 29. In the construction shown in Figs. 5 and 6, the tongues 28, 29 coöperate with the section 30 to lock the brace-member 27 in operative position, whereas in a similar manner the tongues 14, 15 in the construction shown in Figs. 1 and 2, coöperate with the sections 22 of two brace-members to lock both of them in operative position. It is obvious, however, that in the use of the structure shown in Figs. 1 and 2, either brace-member 12 may be allowed to remain idle and flat against

the card 10 while the other brace-member 12 is in use, should it be desired to so employ the easel. When the easel is used on light-weight cards, one of the tongues in the back-section may be allowed to remain out of use and the other tongue relied on to engage the locking section formed in the brace-member and lock said member in operative position.

What I claim as my invention and desire to secure by Letters-Patent, is:

1. An easel comprising a back-section to be secured to a card or the like and a brace-member connected along a weakened line to the vertical edge of said section, said back-section having therein a locking-tongue connected therewith along a horizontal hinge-line so as to be turned outwardly from said section and said tongue having a transverse slot, and said brace-member having integral therewith adjacent to said back-section a vertical locking-section connected thereto along a vertical hinge-line so as to be turned outwardly at an angle to said brace-member, said locking-section having on its end a tongue to enter the said slot in said locking-tongue connected with said back-section.

2. An easel comprising a back-section to be secured to a card or the like and a brace-member connected along a weakened line to the vertical edge of said section, said back-section having therein upper and lower locking tongues provided with transverse slots and connected to said section along horizontal hinge-lines so as to be turned outwardly in opposite directions from said section, and said brace-member having integral therewith adjacent to said back-section a vertical locking-section connected thereto along a vertical hinge-line so as to be turned outwardly at an angle to said brace-member, said locking-section having on its upper and lower ends tongues to enter said slots in said locking-tongues connected with said back-section.

Signed at New York, in the county of New York, and State of New York, this 29th day of November, A. D. 1912.

SAMUEL KISLOVITZ.
